RUDOLF F. SCHOTT, OF SAN FRANCISCO, CALIFORNIA, ASSIGNOR TO JOHN L. KOSTER,
OF SAN FRANCISCO, CALIFORNIA.

ATTACHMENT FOR WATER-SUPPLY PIPES.

1,267,123.

Specification of Letters Patent. Patented May 21, 1918.

Application filed June 27, 1917. Serial No. 177,220.

To all whom it may concern:

Be it known that I, RUDOLF F. SCHOTT, a subject of the Emperor of Germany, residing at the city and county of San Francisco and 5 State of California, have invented certain new and useful Improvements in Attachments for Water-Supply Pipes, of which the following is a specification.

The hereinafter described invention relates to a water saving or economizing attachment for use in connection with the discharge nozzles of water supply pipes for use in hotels, restaurants and households, the object thereof being to economize the water 10 consumption in accordance as to the water quantity desired for use at different periods or times of the day. For instance, in connection with the pantry or kitchen supply nozzles when water is drawn for the washing 15 of certain dishes, a spray stream is preferable to the heavy solid stream usually permitted to flow from said nozzle and where a spray stream is utilized there is less consumption of water than where a solid stream 20 is permitted to discharge. The present invention, therefore, contemplates the form of an attachment whereby the water user may at will permit the outflow of a spray stream 25 delivery from the discharge nozzle or a solid stream therefrom, dependent upon the will 30 of the user of the water. By this means the water consumption may be properly proportioned to the use to which the water is to be placed, thereby creating a material 35 saving in the excess water which at present is permitted to run waste, which is a very important and essential factor to be taken into consideration where water is charged for by meter readings and in such 40 territory where the water supply is of limited quantity and wherein a somewhat heavy charge is made per thousand feet of water 45 consumption.

The hereinafter described invention is one which will appeal to the householder and 50 equally so to the managers of hotels, restaurants and cafés, etc., or such establishments wherein a large monthly consumption of water is made, permitting, as it does, a material saving in water to be made and consequently a material saving in the monthly 55 water bill.

To comprehend the invention, reference should be made to the accompanying drawings, wherein,

Figure 1 is a sectional elevation illustrating the invention as applied to the nozzle of an ordinary valve controlling water supply nozzle, illustrating the controlling valve of the attachment in position for directing 60 the discharge of water into a sprinkler head or rose carried by the attachment.

Fig. 2 is a broken detailed view similar to Fig. 1 illustrating the controlling valve of the attachment turned to close the flow 65 of water into the sprinkler head or rose, and to direct the same as a solid stream through the outlet stem thereof.

Fig. 3 is a sectional plan view taken on the line 3—3 of Fig. 1 of the drawings and 70 viewed in the direction of the arrows.

Fig. 4 is a view similar to Fig. 3 taken on the line 4—4 of Fig. 2 of the drawings and viewed in the direction of the arrow.

In the drawings, the numeral 1 is used to 75 indicate an ordinary discharge nozzle for attachment to the house supply water pipe (not shown), and 2 a valve barrel disclosed in the present case as being detachably mounted on the lower end of the said discharge nozzle. The interior of the barrel 2 is divided by means of the central partition piece or diaphragm 4, and within the barrel above the partition 4 is seated a rotatable plug valve 5. The said rotatable 80 valve 5 is provided in the bottom wall thereof with a plurality of vertically disposed outlet ports 8. The lateral ports 6 in the rotatable valve 5 are adapted to be moved into registry with the lateral ports 9 formed in 85 the vertical wall of the barrel 2, while the vertical ports 8 are adapted to be moved into registry with the vertical discharge ports 10, formed in the central partition piece or diaphragm 4 of the barrel 2. Within 90 the plug valve 5 is fitted a basket strainer 11, which is designed for the purpose of preventing foreign substances passing through the ports 6 of the said valve 5 and the ports 9 of the barrel 2 when the ports are in registry. 95

In the present case, the barrel 2 is illustrated as having formed integral therewith a sprinkler head or rose 12, into which the water discharging through the lateral ports 105 6 and 9 respectively finds its outlet through the perforated bottom 13 thereof, and which discharges therefrom in a spray-like form, or the water stream discharging from the strainer head or rose 12 is broken up into a 110

series of minute spray streams or water jets. It will be understood that the water issuing from the discharge nozzle 1 passes into the sprinkler head or rose 12 when the 5 ports 6 and 9 are in registry; at other times the water issuing from the discharge nozzle 1 passing into the tubular extension or stem 3 through the registering ports 8 and 10, discharging from the said hollow extension 10 or stem 3 in the form of a solid stream.

The movement of the rotary valve 5 is controlled from the exterior of the sprinkler head or rose by means of the spring held handle 14, the stem 14' of which works 15 through a slotted section 15 of the depending rim 15' of the sprinkler head or rose 12, the inner end of said stem 14 being connected by a post 16 to the bottom of the valve 5, said post extending through an aperture in the central diaphragm or bridge 4 of the barrel 2. Each end of the post 16 terminates in a square shank to fit within a square opening in the bottom of the valve 5 and a corresponding opening in the inner 25 end of the stem 14' of the handle 14, being held in place by the heads *a*.

There is interposed between the inner end of the stem of the handle 14 and the partition wall or diaphragm 4 of the barrel 5 30 a helical spring 17, the upper end of the said spring being attached to the wall of the said barrel 5 and the lower end to the stem 14' of the handle 14, the said spring exerting a downward pressure on the stem 14' 35 and post 16, the pressure thus exerted holding the valve 5 seated on the upper face of the partition or diaphragm 4 of the valve 5.

It will be understood that the water flow 40 through the nozzle 1 is controlled by the ordinary hand actuated valve 18.

The valve 5 is thrown or rotated to place the ports 6 and the ports 8 into registry respectively with the ports 9 and 10 of the barrel 2 by means of the before mentioned 45 handle 14, which as swung in one direction places the ports 8 of the valve 5 into registry with the ports 10 of the barrel 2 and on the release of pressure from the said handle the torsional strain of the helical spring 17 50 returns the handle 14 to normal position and places the ports 6 of the valve 5 into registry with the ports 9 of the barrel 2, which is the normal position of the said valve 5.

When in normal position to obtain a spray of water, presuming of course, that the valve 18, is thrown to open the water flow through the nozzle 1, the spring held handle 14 lies, as in Fig. 3, to position the 55 valve 5 so that the lateral ports 6 thereof are in registry with the lateral discharge ports 9 of the barrel 2, at which time the water flow will be from the nozzle through the ports 6 and 9 to the interior of the rose 60 12, from which it escapes through the per-

forations in the bottom wall 13, the escape being in the form of small jets or sprays.

When a heavy or solid stream of water is desired the handle 14 is moved against the tension of spring 17 to place the outlet ports 70 8 of the rotatable valve 5 into registry with the vertical ports 10 of the bridge or partition piece 4 of the barrel 3, which permits of a direct downward flow of the water into the tubular extension or stem 3 of the said 75 barrel 2 and from which it discharges as a solid stream.

While the invention is applicable for use in connection with either of the discharge nozzles of house supply water pipes, it is 80 more particularly designed for use in connection with the hot water discharge nozzle, so that a spray stream of hot water may at certain times be brought into play, while at other times a solid stream of hot 85 water may be permitted to issue through the attachment.

When the water is flowing as a solid stream through the attachment and away therefrom, the stream of flowing water will 90 wash or cleanse the wall of the basket screen 11 of matter or foreign substance which may adhere to or have accumulated on the inner wall or surface thereof, thus maintaining the same clean of such foreign substance. 95

While the invention has been described in its preferred embodiment and is attached to the discharge end of the nozzle 1 by a slip joint connection, it is obvious it may be applied thereto in any well known manner, 100 and I am well aware that changes may be made in the arrangement of the detailed parts herein shown and described without creating a departure from the nature and scope of the invention and I therefore do 105 not wish to be understood as limiting or confining the invention to such details of construction, but to claim the same as broadly as the state of the art will permit.

Having thus described my invention what 110 I claim is:

1. In a device of the class described, the combination with a cylindrical open ended barrel, a diaphragm extending transversely of said barrel and dividing the same into two compartments, a cup shaped plug valve rotatably mounted within said upper compartment and provided in its side and bottom walls with suitable outlet ports, said upper compartment provided in its side wall 115 and in said diaphragm with outlet ports adapted for registering with the respective coöperating ports of said valve, a sprinkler head surrounding said barrel above the lower end thereof and communicating with 120 the outlet ports in the side wall of said upper chamber, an operating post extending centrally of the lower chamber and secured at its upper end to said valve, an operating handle movable within a guide slot formed 125 130

in said sprinkler head wall and connected to said post, said handle capable of movement to operate said valve to position the ports thereof in register with their respective co-
5 operating ports of said upper chamber.

2. In a device of the class described, the combination with a cylindrical open ended barrel, a diaphragm extending transversely of said barrel and dividing the same into two
10 compartments, a cup shaped plug valve rotatably mounted within said upper compartment and provided in its side and bottom walls with suitable outlet ports, said upper compartment provided in its side wall and in
15 said diaphragm with outlet ports adapted for registering with the respective coöperat-

ing ports of said valve, a sprinkler head surrounding said barrel above the lower end thereof, and communicating with the outlet ports in the side wall of said upper chamber, 20 and means coöperating with said valve and capable of movement to operate the same to position the ports thereof in register with their respective coöperating ports of said upper chamber. 25

In testimony whereof I have signed my name to this specification in the presence of two subscribing witnesses.

RUDOLF F. SCHOTT.
